UNITED STATES PATENT OFFICE.

FREDERICK H. BRONNER, OF PORTLAND, OREGON, ASSIGNOR TO IRWIN-HODSON COMPANY, OF PORTLAND, OREGON, A CORPORATION OF OREGON.

DESIGN FOR AN INDIVIDUAL SERVICE-MEDALLION.

52,203.

Specification for Design.

Patented July 23, 1918.

Application filed April 17, 1918. Serial No. 229,207. Term of patent 3½ years.

To all whom it may concern:

Be it known that I, FREDERICK H. BRONNER, a citizen of the United States, residing at Portland, in the county of Multnomah, State of Oregon, have invented a new, original, and ornamental Design for an Individual Service-Medallion, of which the following is a specification, reference being had to the accompanying drawing, forming part thereof.

The figure of the drawing is a plan view showing the design of the individual service medallion.

I claim:

The ornamental design for an individual service medallion as shown.

FREDERICK H. BRONNER.

Witnesses:

CECIL LONG,
ARTHUR HEDEEN.
